(57) **CLAIM**

The ornamental design for a tap, as shown and described.

DESCRIPTION

FIG. 1 is a top front right perspective view of a tap showing my new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof; and,
FIG. 7 is a bottom plan view thereof.
The dashed broken lines are for environmental purposes only and form no part of the claimed design.
